FURNACE CONSTRUCTION

Otto Jaros, Cicero, Ill., assignor of one-half to
William J. Gilbert, Chicago, Ill.

Application November 17, 1934, Serial No. 753,423

1 Claim. (Cl. 110—1)

This invention relates to furnace structures and more particularly to sectionally supported refractory walls and arches in such structures.

The invention in its broader aspects may be applicable to either the air cooled or insulated type of wall.

It is primarily a purpose of this invention to provide a wall structure and arch structure by means of which it is possible to use standard shapes of refractories or fire brick and principally standard supporting structures. Heretofore, so far as I am aware, the conventional suspended arch or sectionally supported furnace wall has been made up of specially shaped refractory units and special metal supporting units both of which command a high premium in original investment and in service replacement. My invention makes it possible to avoid the multiplicity of special shapes of refractories and supporting units thus materially reducing the original installation cost and the cost of replacement.

It is also the purpose of this invention to provide a structure for furnace walls and arches of the utmost simplicity which can be readily applied to all sizes of furnaces and like structures so that the cost of suspended arches and sectionally supported walls is reduced to a point where it is practical to apply them in many small installations that the prior expensive specially shaped structures could not be applied to.

My invention contemplates as a means for carrying out the aforementioned purposes the provision of a very flexible supporting structure utilizing only a small amount of retainers with standard shape brick as the main part of the wall or arch, the brick being mounted and retained in position by bonding of the retainers to the brick by means of air setting or high temperature setting cements.

Other and more specific objects and advantages will appear as the description proceeds in connection with the accompanying drawing wherein the preferred form of the invention is shown.

It is to be understood, however, that the drawing and description are illustrative only and are not to be taken as limiting the invention except in so far as it is limited by the claim.

In the drawing—

Fig. 1 is a vertical sectional view through a portion of a furnace structure showing both the furnace wall and the furnace arch;

Fig. 2 is an enlarged sectional view also taken on the vertical line through the side wall of the furnace;

Fig. 3 is a horizontal sectional view taken on the line 3—3 of Fig. 2; and

Fig. 4 is a sectional view taken on the line 4—4 of Fig. 1.

Referring now in detail to the drawing, the supporting structure for the furnace wall consists of the upright beams such as 10 which may be the ordinary I beam. Running horizontally of the beams are the shelf members 11 which form the base support for the wall refractories. These shelf members are bolted directly to the columns 10 by means of the bolts 12 through the upright flanges 13 thereof. The members 11 may be of any suitable length either continuous for the full length of the wall or in shorter sections abutting each other.

Each of the members 11 has at the upper surface thereof the horizontal groove 14 which may be continuous throughout the length of the base support or in a series of sections. This groove 14 serves as a supporting socket or retainer for the vertical supports 15 which engage the retainers 16. The shelf portion 17 of the member 11 constitutes the supporting unit for carrying the wall section immediately above each member 11. Directly beneath the groove 14, the member 11 is also provided with a downwardly directed groove 18 for retaining the upper ends of the members 15.

At the top of the side wall, the members 15 may be held by a special member 11' which runs horizontally and has only the lower groove 18' formed thereon without any shelf portion such as 17 to project out in the way of the refractories 20 of the arch. These refractories 20 are supported by retainers 21 identical in shape with the retainers 16, and these retainers in turn are carried upon the hanger bars 22 suspended from the rods 23 which hook over the angle irons 24 that run transversely of the furnace and are carried on top of the cross members 10' which are connected to the column 10.

I preferably use thin plates for the retainers 16 and 21 such for example as one-thirty second inch sheet steel so as to maintain as small joints between the bricks as possible. For additional bonding strength between the plate and brick, a hole 30 is provided in plates 16 and 21 in which the cement collects to fortify the strength of the bond. In the case of the insulating fire brick, the natural porosity of their structure permits deeper seepage of the cement thus adding further to the strength of the bond. The retainers may be of other material than metal, such as refractory material of a higher or

comparable tensile strength to that of ordinary fire brick.

The refractory units 25 are ordinary fire brick or insulating fire brick laid on edge and cut out or sawed out as indicated at 26 to rest upon the ledge or shelf 17. Aside from cutting out the portions at 26, no change is made in the standard fire brick shape throughout the major portion of the refractory lining. The reason for recessing the brick at 26 is to provide protection for the horizontal ledge 17 of the supports 11 from the radiant heat of the furnace.

The method of laying up the brick is to place a thin layer of air setting, or high temperature setting refractory cement on the ledge 17. The base brick 25 is then laid in place, one end being supported on the ledge 17 and the other end on a filler block 32 which is carried by the column of refractory below. These filler blocks are only of a temporary nature to permit the proper support of the refractory prior to the bonding of the plates 16 to refractory units 25 and 27 which occurs with the setting of the cement. The filler blocks may be of wood which can be left in place to burn out when the furnace is in operation or can be removed after the cement has set, which in case of air setting cement is only a matter of a few hours.

After the base brick 25 is placed in position, the vertical metal support 15 is placed in grooves 14 and 18 for positive retainment. Before inserting the supports 15 in the grooves, the required number of plates 16 are threaded on the supports 15. The plates 16 are then slid up to the top extremity of support 15 where they are supported by a wedging action which develops because of the unbalanced weight of the plates in their mass relation to the support. The plates are thus kept out of the way until they are needed. After the base brick 25 is in position, a thin layer of refractory cement of either the air setting or high temperature setting variety is applied to the top. Then one of the retaining plates 16 is released from the top and placed in position. Then a brick whose underside has been coated with a cement is placed on top of the plate and base brick, thus completing one layer of the unit section. The balance of the brick and plates are then placed in position and in the series noted in Fig. 1.

I have found in practice that a very thin layer of cement between the brick is all that is necessary for ample bonding of the plates and the brick. This cement is used throughout the length of the bricks and over the fire contact faces as indicated at 28 and 29. It can be obtained commercially with such characteristics that it will resist temperature of 2500° F. and upward, thus assuring a very strong bond between the bricks and the plate.

The bond between the plate and the cement and between the cement and the brick is so strong that, when force is applied to remove the plate from the side of a brick, the material of the brick adjacent the cement breaks off with the cement thus showing that the bond between the metal and the cement and between the cement and the brick is greater than the tensile strength of the brick itself.

When the section of brick is completed up to the next shelf, a suitable filler 31 is inserted, this being a composition of resilient and refractory substances having the property of expansion and contraction as well as being heat resistant, to

compensate for temperature changes in the refractory structure.

Where the insulating fire brick is used, the temperature to which the plates 16 may be subjected is only a few hundred degrees and, therefore, ordinary sheet steel will not be damaged when used for the plates 16. This insulating fire brick is a very porous structure, much lighter than ordinary fire brick and therefore capable of withstanding a high temperature on one end without being heated very much at the other end. The pores of the insulating brick are filled with the same air setting cement on the faces exposed to the interior of the furnace as indicated by the cement at 29 in Fig. 2.

Where ordinary fire bricks are used because of the relatively high heat conductivity, I use a special heat resistant steel for the plates 16 so that they will not be destroyed by the high temperature produced at the back ends of the fire brick. Regardless of the refractory material used, however, the bonding of the plates to the brick is done in the same fashion.

The side walls when laid up have the joints staggered as it is immaterial so far as the plates 16 are concerned whether they bond to two bricks on one side or only to one brick. This also is an advantage over most of the sectional supported wall structures as it permits breaking of joints where the special tile shapes make it difficult to get this result.

In the arch structure, the ordinary shapes of fire brick indicated at 20 are bonded to the retainers with the same cement used in the side walls and with plates 21 identical with plates 16 being used as retainers. Preferably, the plates are interposed in every other joint between the bricks. The bricks are bonded to the plates before being installed in the arch, and then, after the cement has set, the individual plates with the bricks carried thereby are hung upon the members 22. Since the bonding strength of this cement with the metal plate and with the brick is so great, it will readily carry the weight of the arch so that the plates 21 constitute the load bearing supports for the arch. It is, therefore, unnecessary to provide any holes or notches or slots in the brick and a much greater strength is obtained because of the wide surface contact between the cement and refractory material on the one hand and between the cement and the metal plate on the other hand.

It is a well known fact that fire clay or fire brick has little tensile strength. Therefore, when it is supported by means of any notch or opening cut into the brick, the entire unit is so weakened as to cause considerable loss due to breakage under its own weight. All of this is avoided in the present structure and in addition, the special shapes are unnecessary.

The particular supporting structure I have shown is particularly useful in sectionally supported walls because of the great flexibility thereof both in assembly and adjustment for expansion and contraction. It will be noted that the upright supports 15, which in the present instance are shown as simple metal rods, are free to slide horizontally in the grooves 14 and 18 and also free to move up or down a limited amount. Further, the plates 16 can slide up or down upon the rods 15 to adjust themselves.

The furnace may be repaired either from the inside or outside by removing the rods such as 15 and pulling the brick out from the back or into the furnace. This greatly facilitates the

5 repair of furnace walls and, as no special shapes of refractories are required, the fire brick used may be purchased in the open market at the most advantageous price. This structure also avoids the difficulties that furnace operators undergo in obtaining the special shapes of refractory tile and metallic supports as it is not necessary to carry a large stock of different shapes or to wait until special orders may be filled.

10 From the above description, it is believed that the construction and advantages of this device will be readily apparent to those skilled in this art.

15 Having thus described my invention, what I

claim as new and desire to secure by Letters Patent is:

The combination in a furnace structure or the like of a supporting framework, a lining therefor of fire brick, certain of said fire brick being 5 bonded together by an air setting high temperature resistant cement and retaining members bonded to said brick lining by said cement and having no frictional engagement with the brick and connected with the framework, said retaining members having openings therein, and said framework having vertically and horizontally adjustable members extending through said openings.
